and in Spain May 13, 1929

7 Claims. (Cl. 140—93)

The invention relates to an improved machine for fastening by means of wire, which, with an extremely simple mechanism, enables the different operations of stretching, twisting and cutting the wire to be unified in one working cycle requiring a single operation which can be performed in a few seconds.

Various machines of this kind are already known the working of which provides for the tautening of the wire on the case or bundle to be fastened, the twisting and cutting of the wire, but in separate operations. That is to say, first the tautening has to be done with the aid of traction racks or rollers, in which the wire is drawn taut by operating a lever or turning the roller until the required tension has been reached and then, after this operation has been carried out, the wire is twisted by a separate device and its surplus ends are cut off.

Other types of machines existing in the market require special wires provided with notches or stops and previously cut to certain lengths, so that they also effect the operation of fastening in two different stages.

The advantages of the apparatus forming the subject of the present invention consist in the following facts:—

(1) Wire of any type of thickness may be used, taken straight from a roll, without requiring to be cut beforehand.

(2) Extreme simplicity of the mechanism.

(3) All the operations are effected by one movement to and fro of a single lever, thus minimizing the time and labor required for working.

To enable the apparatus to be thoroughly understood, it is described hereunder with reference to the drawings attached hereto, in which Fig. 1 is a side view of the fastening machine shown placed on a case to be fastened.

Fig. 2 is a similar view to that of Fig. 1, showing the operation of the machine for stretching the wire.

Fig. 3 shows the plaiting of the wire as effected by the machine.

Fig. 4 is a view of the back of the machine.

Figs. 5, 6, 7, 8 and 9 represent various sections of the machine, showing details of its mechanism and manner of working.

As will be seen from these drawings, the machine is composed of the following parts:—

A sole 1, forming the base of the mechanism and supporting all its parts, is provided with two lugs 2, fitted on either side of the sole near its centre, which lugs carry a fixed horizontal shaft

3, on which are fitted, independently of one another, the three following pieces:—the spur pinion 4, spiral gear 5 and hub 6 of the swinging arm or lever 35.

The sole 1 is provided lengthwise with a rectangular body 7, the inside of which is hollowed throughout its length so as to take a rack 8 which slides in the hollow space and engages with the pinion 4. In the bottom of the hollow space is a rod 9 fitted with two spiral springs 10 and 11. On this rod slides a stop 12, which is solid with the rack and is acted on by the springs 10 and 11, transmitting their action to the rack, as will be explained when dealing with the operation of the apparatus (Fig. 4).

At the left end of the rack a clamp is provided for holding the end of the wire that is to be cut, which clamp is composed of a lever 13 having a toothed cam head and of a small block, also toothed, between which the wire is gripped fast in the manner shown in Fig 2. The tensile strain of the wire itself causes the latter to fit tightly into the indentation 15, thus strengthening the grip.

On the right hand side of the sole a similar clamp 16 is provided, symmetrical and identical in working with the other clamp, and gripping the free end of the wire. The lever 17 of this clamp in its turn operates a small lever 18, which serves as a stop retaining the wire and preventing its displacement when it is being stretched and its twisting is begun. Lever 18 is mounted freely on its pivot and when lever 17 is raised it raises 18 by its action on the latter's projecting part 18'. On the other hand, when lever 17 is lowered and the wire is secured, lever 18 falls under its own weight and its projecting part 18'' comes to lie in front of the wire as shown in Figure 2 of the drawings, and prevents this wire from slipping out of the position in which it is secured, under the twisting effort.

On a projection 19 of the body of the base 1 and fitted on a shaft 20 is a retention tooth 21, which is held constantly on the rack by the spring 22.

A knife 23 oscillating on a shaft 24 screwed to the transverse projection 25 of the left hand rear part of base 1, serves for cutting the wire. This knife of special shape (see particularly Figs. 8 and 9) has its stroke limited by a pin 26 which passes through it by an opening 27 made near the cutting edge 28; the spiral spring 29 resting underneath on the base 1 keeps the knife 23 normally raised.

In the upper part of the knife 23, on the side

100

105

110

facing the spiral gear 5, a pin 30 is housed, which is held constantly against the rear plane of 5 by a spiral spring 31. The spiral gear 5 has two notches 32, situated at diametrically opposed points, into which the pin 30 enters; it also has two recesses 33 similarly situated, which recesses are engaged by the point 34' of tooth 34 provided on the operating lever 35, which thus carries the gear 5 along with it.

10 The operating lever has fitted to it the following parts:—a pressure rod 36, which is normally held off or upwards by a spring 37, but can be brought into action downwards by pressing on a knob 38 provided on the rod.

15 This rod 36 operates a catch 39 swinging on shaft 40 fixed to one side of the lever 35. Another catch 41 projects from that side and moves the tautening tooth 42, which swings on shaft 43, fixed to another side in the rear of the lever. To

20 effect this movement the projecting catch 41 engages with the likewise projecting point 44 of the tautening tooth 42. The end 45 of this same tooth projects on the opposite side and, at the end of the stroke of the lever, bears upon pin 30.

25 The tautening tooth proper is formed of the point 42, which engages with the teeth of pinion 4. A spring 46 holds the tautening tooth 42 in engagement with the pinion 4. On the side of the lever 35 that is opposite and parallel to the

30 one occupied by the tautening tooth 42, and mounted on shaft 43' is the dragging tooth 34, which, by engaging its point 34' in the recesses of the spiral gear 5 causes the latter to move when required. A tail 47 of this tooth is tripped

35 by the catch 39 so that, when the rod 36 is pressed down, the point 34' of tooth 34 is withdrawn from the recesses 33 and the gear 5 released.

Geared with the underside of the spiral gear is a pinion 48 intersected in an axial direction by a 40 groove 49 housing the wires. When the latter are being interlaced, this pinion exerts a strong effort on its right end under the thrust of the spiral teeth. To minimize friction a ball bearing, 50, shown in Fig. 5, is provided at this end, which 45 prevents the wear and wedging effect that would otherwise be produced.

The working of the apparatus is as follows:—

The apparatus, as shown in Fig. 1, is placed on the package C that is to be fastened. The free 50 end of the wire is gripped by the lever and clamp 16—17. The wire is then passed through the groove 49 of pinion 48, is led around the package, and is again passed through groove 49 alongside the former strand of wire, whereupon it is gripped by the lever and clamp 13—14 of the rack. The wire is not cut, but is left hanging from the roll.

The apparatus being in this position, as shown by Fig. 1, steps are taken to tauten the wire, for which purpose the lever 35 is turned over an arc 60 of a circle, as shown in Fig. 2. In the course of this operation of the lever 35, the tautening tooth 42 carries the pinion 4 with it, as its point is engaged between two teeth of the pinion, by the action of spring 46 (Fig. 4). As the pinion 4 65 engages with rack 8, the latter is forced to move in the guideway in the base 1, and the end of the wire that is gripped by the clamp 14 and thus moves with the rack is forced to exert an effort of traction on all the wire encircling the container 70 and duly stretch it.

Provision has been made for the case that, in spite of lever 35 having reached the end of its stroke, the wire should not be taut enough to give a good fastening. For this purpose, if the 75 wire should still be slack after having turned the

lever through an angle of 180°, the latter need only be returned to its original position and the operation repeated. This is rendered possible by the retaining tooth 21, which holds the rack 8 in any of its positions (see Fig. 2) and maintains the tension until the displacement of the rack is increased by the fresh operation just mentioned.

80 Provision has also been made for the possibility that the wire, both when being tautened and later when being twisted, may leave its groove. To avoid this, the lever 18 is provided so as to contain the wire and prevent its being jerked out of its groove.

85 When the wire has been drawn sufficiently taut and the lever 35 has been brought to its extreme position on the right of the apparatus, as shown by the dotted line in Fig. 2, the tooth 34 under action of its spring 52 causes its point 34' to enter recess 33 in the spiral gear 5.

90 Thereby, on again moving the lever 35 to its original position, shown in Fig. 1, the lever will carry the spiral gear 5 with it, causing it to make half a turn. The spiral pinion 48 gears with the wheel 5 underneath the same, the number of its teeth being chosen so that during half a 100 revolution of the wheel 5 it makes an exact number of revolutions so as to leave its channel 49, at the end of those revolutions, exactly coinciding with the groove by which the wire is introduced and the latter can be withdrawn from 105 inside the pinion.

95 When this pinion 48 turns, the two strands of wire, introduced into its channel 49 and so arranged that the axis of rotation intersects them by half (see Fig. 1), are forced to twist round one 110 another, forming two spiral knots of opposite pitches, which constitutes a perfect type of fastening, obtained without any foreign elements, as the two ends of the wire are, as it were, soldered together and it is impossible for them to 115 slip. Fig. 3 shows the interlacing of the wire effected by the machine.

120 The end of the operation is constituted by the automatic cutting of the wire and the likewise automatic return of the rack 8 to its position of rest. For carrying out these two operations the following mechanism is provided:—When lever 35 reaches the position shown in Fig. 1 (see this figure and particularly Fig. 4), the wire has already been interlaced and, accordingly, the rack 125 can return to its original position, for which purpose tooth 42 holding pinion 4 and tooth 21 holding the rack 8 must be released. On the upper part of knife 23 a pin 30 is provided, which, on striking point 45 of tooth 42 disengages this tooth from the pinion 4 almost at the same time as the stop 53 on the lever 35 raises tooth 21 off the rack by pressing on its opposite end and obliging it to swing up on its shaft 20. The rack, being thus free to re-enter the base 1, does so rapidly 130 under effect of the spring 11. To prevent excessive blows on the return of the rack, a spring 10 is provided to deaden the shock.

135 Simultaneously the lever 35 presses on the upper part of the knife 23 (Fig. 9), causing it to swing on its shaft 24 and cut, with its edge 28, the front wire lying in the groove, i. e. the part of the wire attached to the roll. A spring 29, fitted on the knife, raises the latter when the lever no longer acts on it, thus allowing the wire 140 to be withdrawn from inside the apparatus.

145 To allow of an exact coincidence of the channel of the spiral pinion and the groove in the base, through which grooves the wire has to pass in order to withdraw the machine after the fas- 150

tening has been effected, a pin 30 is provided which, at the end of the stroke, enters into the notch 32 on the spiral gear-wheel 5, under action of spring 31.

5 Also, on the operating lever 35 a rod 36 is provided, which, when acted on by the knob 38, moves the catches 39 and 41, obliging them to swing and release the spur pinion 4 and spiral gear 5, so as to be able to move the lever 35 without its 10 performing any work. This movement is necessary, for example, when the tension first given to the wire is not sufficient and the wire requires to be drawn tauter, as for that purpose the lever 35 has to be returned to its initial position without 15 taking the spiral gear with it as, otherwise, this latter wheel would turn and cause the wire to be plaited before it had been sufficiently tautened.

It will of course be understood that the manner of realization presented merely refers to an example of execution, and the arrangement of the mechanism and measurements and materials used 20 may be varied without affecting the fundamental principle of the invention.

We claim:

25 1. In apparatus for wiring cases, bales and the like, means for tensioning the wire, means for twisting the wire, means for cutting the wire, and a single lever and means associated therewith for actuating the tensioning, twisting and cutting means, said tensioning means including a longitudinally movable rack bar having wire gripping means and a pinion engaging said rack bar; said twisting means including a revolute element and a gear wheel geared thereto and said lever being 30 provided with means for successively operating the gear wheel, the pinion and the cutting means.

35 2. Apparatus as claimed in claim 1, in which the tensioning means comprises a longitudinally movable rack bar having wire gripping means and a pinion engaging said rack bar; the twisting means includes a revolute wire twisting element and the gear wheel engaged therewith and in which the lever is provided with means to impart intermittent rotation successively to the pinion 40 and the gear wheel according to the direction of movement of the lever and in which the lever is also provided with means for actuating the cutting means.

45 3. Apparatus as claimed in claim 1, in which the tensioning means comprising a longitudinally movable rack bar having wire gripping means and a pinion engaging said rack bar; the twisting means includes a revolute wire twisting element and the gear wheel engaged therewith and in 50 which the lever is provided with means to impart intermittent rotation successively to the pinion

and the gear wheel according to the direction of movement of the lever and in which the lever is also provided with means for actuating the cutting means and in which the cutter is a movable knife arranged for operation by a lever at the conclusion of the operation of the twisting means.

5. Apparatus as claimed in claim 1, in which the tensioning means comprises a longitudinally movable rack bar having wire gripping means and a pinion engaging said rack bar; the twisting means includes a revolute wire twisting element and the gear wheel engaged therewith and in which the lever is provided with means to impart intermittent rotation successively to the pinion and the gear wheel according to the direction of movement of the lever and in which the lever is also provided with means for actuating the cutting means and in which the lever has pawls for respectively engaging the pinion and the twisting gear and means for operating said pawls.

6. Apparatus as claimed in claim 1, in which the tensioning means includes a longitudinally movable rack bar having wire gripping means and a pinion engaging said rack bar; in which the twisting means includes a revolute element and a gear wheel geared thereto and in which the lever is provided with means for successively operating the gear wheel, the pinion and the cutting means, and a stop element to hold the rack bar against casual reverse movement while the wire is tensioned.

7. Apparatus as claimed in claim 1, in which the tensioning means includes a longitudinally movable rack bar having wire gripping means and a pinion engaging said rack bar; in which the twisting means includes a revolute element and a gear wheel geared thereto and in which the lever is provided with means for successively operating the gear wheel, the pinion and the cutting means provided with a longitudinal groove open at one side thereof for the reception of the wire.

8. Apparatus as claimed in claim 1, in which the tensioning means includes a longitudinally movable rack bar having wire gripping means and a pinion engaging said rack bar; in which the twisting means includes a revolute element and a gear wheel geared thereto and in which the lever is provided with means for successively operating the gear wheel, the pinion and the cutting means provided with a longitudinal groove open at one side thereof for the reception of the wire and also includes means to prevent casual disengagement of the wire from said groove.
